UNITED STATES PATENT OFFICE.

JESSE JAMES SPARGO, OF ALFION, NEW YORK.

DESIGN FOR A POISON-BOTTLE.

50,561.

Specification for Design.

Patented Apr. 3, 1917.

Application filed November 9, 1916. Serial No. 130,478. Term of patent 3½ years.

To all whom it may concern:

Be it known that I, JESSE J. SPARGO, a citizen of the United States, residing at Alfion, in the county of Orleans and State of New York, have invented a new, original, and ornamental Design for Poison-Bottles, of which the following is a specification, reference being made to the accompanying drawing, forming part thereof.

The figure is an elevation of a poison bottle, showing my new design.

I claim:

The ornamental design for a poison bottle, as shown.

JESSE JAMES SPARGO.

Witnesses:

W. CRAWFORD RAMSDALE,
Mrs. J. J. SPARGO.
